(57) **CLAIM**

The ornamental design for a vented helix brush, as shown and described.

DESCRIPTION

FIG. 1 is a top, perspective view of a vented helix brush, showing my new design.

FIG. 2 is a bottom, perspective view thereof.

FIG. 3 is a front view thereof. The rear view is the same as the front view.

FIG. 4 is a right side view thereof. The left side view is the same as the right side view.

FIG. 5 is a top view thereof; and,

FIG. 6 is a bottom view thereof.

The dash-dash broken line shown in the drawings represent portions of the vented helix brush, and form no part of the claimed design. The dot-dash style of broken lines shown in the drawings represents the boundary of the claim, and forms no part of the claimed design.
